(57) **CLAIM**

The ornamental design for a snow tool as shown and described.

DESCRIPTION

FIG. 1 is a perspective view of the snow tool showing our new design;

FIG. 2 is a front view of the snow tool;

FIG. 3 is a rear view of the snow tool;

FIG. 4 a top view of the snow tool;

FIG. 5 is a bottom view of the snow tool;

FIG. 6 is a first side view of the snow tool; and,

FIG. 7 is a second side view of the snow tool.

The broken line in the drawings illustrates portions of the snow tool and forms no part thereof.
